MACHINE FOR WRAPPING SWEETS AND
THE LIKEFrederick Grover, Leeds, England, assignor to The
Forgrove Machinery Company Limited, Leeds,
EnglandApplication September 9, 1935, Serial No. 39,867
In Great Britain December 15, 1934

8 Claims. (Cl. 93—5)

This invention relates to machines for wrapping sweets and the like of the type which are usually described as twist wrapping machines wherein the opposed ends of the wrappers are twisted by combined rotary and reciprocating movements imparted to two pairs of grippers adapted to operate simultaneously on the ends of the wrappers.

The object of the present invention is to effect certain improvements in such machines to make them more adaptable to different sizes of sweets or the like and thereby increase the efficiency of the machine.

According to this invention, in a machine of the type specified above the gripper is provided with an adjustment device to enable the amount of the reciprocating movements imparted to it to be varied within predetermined limits. The adjustment device is preferably of such a form that the amount of reciprocating movement is infinitely variable within said limits.

The invention is particularly applicable to grippers which are continuously rotated but it includes the application of the device to intermittently rotated grippers.

In a preferred construction, the machine comprises the combination of mechanism for wrapping the sweets or the like in paper or other material and conveying the sweets and wrappers to the twisting position, a pair of grippers adapted to operate simultaneously on opposite ends of the wrapper, mechanism for continuously rotating said grippers, mechanism for reciprocating said grippers towards and away from each other and an adjustment device in the mechanism for reciprocating said grippers to permit of adjustment of the amount of reciprocating movement imparted to said grippers.

In machines of the type specified above, a device, usually in the form of a rack rod engaging with pinions on the gripper jaws, is provided for opening these jaws. The rack rod reciprocates with the grippers and since the amount of reciprocation of the grippers is, under the present invention, to be adjustable, the opening of the grippers would consequently be varied, which is undesirable. To avoid this variation a device is provided for imparting a constant opening movement to the gripper jaws irrespective of the variation of the reciprocating movement of the grippers.

A practical embodiment of a wrapper gripper according to this invention is illustrated, by way of example, in the accompanying drawings, in which:—

Fig. 1 is a side elevation of one of the wrapper grippers, together with its supporting and actuating mechanism.

Fig. 2 is a plan view of the apparatus shown in Fig. 1.

Fig. 3 is a section on the line 3—3 in Fig. 1.

The opposed grippers are each provided with separate actuating mechanism, the actuating mechanism for one gripper being connected by means of a common shaft to that of the other gripper so that the two grippers are adapted to operate simultaneously on the ends of the wrapper. The grippers and actuating mechanism are of the same construction, consequently only one of these is illustrated in the drawings.

Each gripper *a* is carried by a spindle *b* mounted for rotation and axial movement in a bracket *c* which extends beneath and carries the whole of the said actuating mechanism including the end of the shaft *e*. Gearing, comprising an elongated spur wheel *d* on the spindle meshing with a spur wheel *d*¹ on the shaft *e*, is provided for rotating the spindle *b* continuously from said common shaft *e*, while permitting the spindle *b* to be reciprocated endwise. Reciprocating motion of the spindle *b* is obtained from a cam *f* mounted on said shaft *e* and operating a lever *g* which is pivoted to the bracket *c* at *g*¹ and has a forked end *g*¹ for engagement between flanges *b*¹ on the end of said spindle *b*.

The follower *f*¹ on the cam *f* is connected to said lever *g* by means of a bell crank lever *h* which carries said follower *f*¹ at the end of one its arms. The other arm *h*¹ of the bell crank lever *h* extends parallel (in the plan view) to an arm *g*² on the lever *g* and the said arm *h*¹ is of channel section (see Fig. 3) into which a rectangular block *h*³ is slidably fitted to form part of a driving adjustable coupling between the lever *h* and the lever *g* whose arm *g*² is constructed to house the remaining elements which complete the adjustable connection between the lever *h* and the lever *g* and control the position of the block *h*³ in the channelled arm *h*¹.

The elements which complete the adjustable connection between lever *h* and lever *g* consist of a pin *h*⁵ passing rotatably through the block *h*³ and extending through a slot *g*³ formed in the arm *g*² of the lever *g* with said pin further extended to terminate in a cross-head *g*⁴ to which it is rigidly attached. The cross-head *g*⁴ is drilled and threaded to receive an adjusting screw *g*⁵ by means of which the cross-head is moved along the slot *g*³ carrying with it the block *h*³ and sliding the block along the chan-

nelled arm h^1 . When the block h^3 is, as shown in the accompanying drawings, at the outermost end of the bell crank lever h the lever g derives its maximum movement but when the block h^3 is moved towards the pivot h^2 of the bell crank lever h , which pivot is mounted on the bracket c , the movement of the lever g is reduced proportionally. When the block h^3 is moved to coincide with the pivot h^2 on the lever h there is no movement of the lever g , and therefore, by means of the adjusting screw g^5 the reciprocating movement of the jaws a^1 can be changed by infinitely small graduations from a maximum value down to zero.

15 In order to keep the opening movement of the twisting jaws constant irrespective of the amount of reciprocating movement imparted to the gripper spindle b , the operating lever i for operating the rack rod j by which the jaws are opened in the well known manner is mounted by means of a pivot i^1 on the lever g . This jaw opening lever i is pivotally connected to one end of a link k the other end of which is connected by a pivot k^1 to one arm of a bell crank lever m , the other arm of which is operated by a cam n through the follower n^1 . The bell crank lever m is mounted on the bracket c . The pivot k^1 is arranged approximately coincident with the pivot g^* of the lever g so that the jaw opening lever i moves with the spindle and with the rack rod and thus the relationship of the lever i to the spindle b is not varied by the amount of reciprocation of the gripper spindle. The rack rod and pinion for opening the jaws are of the well known construction.

20 The bracket c on which the spindle b of the gripper and its actuating mechanism are mounted extends from a point just behind the gripper to a point adjacent to the end of the shaft e . The bracket is adjustable by known means consisting of the screw l , so as to enable each gripper to be moved towards and away from the other and thus set the gripper to suit different lengths of sweets and the like. It is an important feature of this invention that the reciprocating movement of the grippers can be varied after the grippers have been adjusted to suit the length of sweet or the like without disturbing the inner position of the gripper jaws determined by the setting adjustment which arises from the fact that the devices for adjusting the reciprocating movement are mounted on the bearings c which are adjustable as a whole by means of the screw l . In other words adjusting bracket c does not disturb the adjustment of the spindle reciprocating and the jaw opening means, because the levers h , g and m are pivotally mounted on the bracket c .

25 60 What I claim as my invention and desire to secure by Letters Patent is:—

1. Twist grippers for wrapping machines comprising, gripping jaws, a spindle carrying said jaws mounted for rotation and endwise reciprocation, a gripper driving shaft, gearing on said shaft for rotating said spindle, a cam on said shaft for reciprocating said spindle, two levers one of which engages with said reciprocating cam and the other of which engages with the spindle, means for adjustably interconnecting one of said levers to the other in order to permit the amount of reciprocating movement imparted to the grippers to be varied within predetermined limits.

75 2. Twist grippers for wrapping machines com-

prising, gripping jaws, a spindle carrying said jaws mounted for rotation and endwise reciprocation, a gripper driving shaft, gearing on said shaft for rotating said spindle, a cam on said shaft for reciprocating said grippers, two levers one having guides and the other having a slot, one of said levers engaging with said reciprocating cam the other lever engaging with the spindle, a block slideable in said guides and a pin on said block engaging in the slot in the other lever, means for adjusting said block towards and away from the pivot of one of the levers in order to permit the amount of reciprocating movement imparted to the grippers to be varied within predetermined limits.

3. Twist grippers for wrapping machines comprising, gripping jaws, a spindle carrying said jaws mounted for rotation and endwise reciprocation, a bearing carrying said spindle adapted to be adjusted to vary the position of the jaws to suit different sizes of articles to be wrapped, a gripper driving shaft, gearing on said shaft for rotating said spindle but permitting it to be moved endwise, a cam on said shaft for reciprocating said grippers, two levers mounted on said bearing one having guides and the other having a slot, one of said levers engaging with the spindle, a block slideable in said guides and a pin on said block engaging in the slot in the other lever, means for adjusting said slide towards and away from the pivot of one of the levers in order to permit the amount of reciprocating movement imparted to the grippers to be varied within predetermined limits.

4. Twisting mechanism for wrapping machines comprising a pair of grippers adapted to operate on opposite ends of a wrapper, each having a pair of gripping jaws, a spindle carrying each pair of jaws, means for mounting said spindle for rotation and endwise reciprocation, means for 40 rotating said spindle, means for reciprocating said spindle, means for adjusting the reciprocating movements imparted by said reciprocating means to said spindle, means for adjusting said mounting means for the spindle to vary the 45 initial distance of the grippers from each other whereby the adjustment of either of said adjusting means can be made without affecting the other, and means for imparting a constant opening and closing movement to said gripping jaws, 50 irrespective of the adjustments effected by said adjusting means.

5. Twisting mechanism for wrapping machines comprising a pair of grippers adapted to operate on opposite ends of a wrapper, each having a pair of gripping jaws, a spindle carrying each pair of jaws, means for mounting said spindle for rotation and endwise reciprocation, means for 55 rotating said spindle, means for reciprocating said spindle, means for adjusting the reciprocating movements imparted by said means to said spindle, means for imparting an invariable opening and closing movement to said gripping jaws, means for adjusting said grippers towards and 60 away from each other, either of said adjusting means being adapted to permit of its own adjustment without affecting the other and without affecting the opening and closing movements of said gripping jaws.

6. Twisting mechanism for wrapping machines comprising a pair of grippers adapted to operate on opposite ends of a wrapper, each having a pair of gripping jaws, a spindle carrying each pair of jaws, means for mounting said spindle 75

for rotation and endwise reciprocation, means for rotating said spindle, a cam, mechanism actuated by said cam for reciprocating said spindle, a separate means for adjusting the said mechanism to vary the reciprocating movements imparted by said reciprocating means to said spindle, a separate means for adjusting said mounting means for the spindle to vary the initial distance of the grippers from each other, both of said 5 adjusting means being so arranged that the adjustment of either can be made without affecting the other, and means for imparting a constant opening and closing movement to said gripping jaws, irrespective of the adjustments effected by 10 either of said adjusting means.

7. Twist grippers for wrapping machines comprising a pair of grippers adapted to operate on opposite ends of a wrapper, each having a pair of gripping jaws, a spindle carrying each pair of jaws, means for mounting said spindle for rotation and endwise reciprocation, means for rotating said spindle, a cam for reciprocating said spindle, two levers one of which engages with said reciprocating cam and the other of which engages with said spindle, adjusting means for adjustably interconnecting one of said levers to the other in order to permit the amount of reciprocating movement imparted to the grippers to be varied within predetermined limits, separate 15

means for adjusting said mounting means for the spindle to vary the initial distance of the grippers from each other whereby the adjustment of either of said adjusting means can be made without affecting the other, and means for imparting a constant opening and closing movement to said gripping jaws, irrespective of the adjustments effected by either of said adjusting means. 20

8. Twisting mechanism for wrapping machines comprising a pair of grippers adapted to operate on opposite ends of the wrapper each having a pair of gripping jaws, a spindle carrying each pair of jaws, means for mounting said spindle for rotation and endwise reciprocation, means for rotating said spindle, means for adjusting by infinitely small changes between zero and a predetermined maximum the reciprocating movements imparted by said reciprocating means to said spindle, means for adjusting said mounting means for the spindle to vary the initial distance of the grippers from each other, each of said adjusting means being so arranged that the adjustment of either can be made without affecting the other, and means for imparting a constant opening and closing movement to said gripper jaws irrespective of the adjustments effected by either of said adjusting means. 25
